UNITED STATES PATENT OFFICE.

GEORGE S. RACKLYEFT, OF BUFFALO, NEW YORK, ASSIGNOR OF ONE-HALF TO CHARLES W. HOUSE, OF HOLLAND, NEW YORK.

MARBLE-SHOOTER.

No. 908,328.

Specification of Letters Patent.

Patented Dec. 29, 1908.

Application filed June 17, 1908. Serial No. 439,013.

To all whom it may concern:

Be it known that I, GEORGE S. RACKLYEFT, a citizen of the United States, residing at Buffalo, in the county of Erie and State of New York, have invented a Marble-Shooter, of which the following is a specification.

My invention relates to toys, and is more especially an improvement in that particular class of toys which are employed in children's games for the purpose of shooting marbles, and are known as marble-shooters.

The principal objects of my invention are to provide a marble-shooter which is simple in construction, can be easily operated, and will project the marble in a direct line with considerable force and accuracy, thereby providing an effective device or toy for the amusement of children in their games.

With these principal objects in view my invention consists of a block recessed at one end to receive the marble, a spring-actuated rod or plunger working longitudinally through the block and adapted to project the marble, and a bent spring plate or trigger through which the rod or plunger projects and by which it is held retracted; all as hereinafter particularly described and specifically set forth in the appended claims.

In the accompanying drawings, which form a part of this specification:—Figure 1 is a perspective view of a marble-shooter constructed in accordance with my invention. Fig. 2 is a vertical longitudinal sectional view through the device. Fig. 3 is a plan view.

Like numerals of reference indicate like parts in all the figures of the drawings.

In carrying out my invention I employ in the first instance a rectangular wooden block 5, and cut the forward part of the top away so as to leave a projecting portion 6 at the rear end thereof, and also cut out the front end of said block to form a vertical recess 7, the opposite vertical walls 8 of which converge slightly towards the rear wall. Upon the bottom of the block is glued or otherwise secured a strip 9, which at its forward end extends across the recess 7 and forms the bottom thereof, so that the marble which is placed in said recess may rest upon said strip. The strip 9 may be either cardboard or thin sheet metal, the latter material being preferred, inasmuch as it will not wear out so quickly by contact with the ground or other

surface upon which the device is placed in use.

The block is provided with a longitudinal bore 10, extending therethrough from end to end, and in this bore is adapted to slide a rod or plunger 11, provided at its rear end with a head 12 and adjacent its front end with a notch 13. This rod or plunger is longer than the block so that it may project a suitable distance beyond the front end thereof, the forward movement being limited by the head 12 striking the rear end of the block, and this rod or plunger is actuated or forcibly projected by means of a rubber band 14, which is passed around the sides and ends of the block and over the head 12 of the rod or plunger. Where the rubber band passes around the corners of the block the latter is notched, as at 15, so as to hold said band in place, and the head of the rod or plunger is also recessed transversely, as at 16, for the same purpose, as well as to keep the notch 13 at the under side of the rod to properly engage the trigger-plate, hereinafter described.

For the purpose of holding the rod or plunger retracted, as well as to serve as a trigger for releasing said rod or plunger, I provide an L-shaped spring plate 17, the upper horizontal member of which is attached at its rear end in a recess therefor in the projecting portion 6 of the block, while the other or vertical member depends in the recess 7 and is provided with an opening 18 through which the rod or plunger passes. The spring tendency of this plate is upward, and the horizontal member thereof normally lies a slight distance above the depressed portion of the top of the block, and in this position of the spring plate it engages the notch 13 in the rod or plunger when the latter is retracted, as illustrated clearly in Fig. 2 of the drawings.

As will be readily seen the rod or plunger when retracted is under tension of the rubber band, being held by the L-shaped spring plate or trigger, and when released by depressing said spring plate or trigger it will be projected quickly and forcibly, so that an object, as a marble, 19, which may be in the recess 7 in front of said rod or plunger will be projected thereby out of the device. That part of the rubber band which extends across the recess 7 is employed for the purpose of holding the marble in place until the

rod or plunger is released, yieldingly engaging the upper part of the marble so that the latter may freely pass out of the device.

In using the device the rod or plunger is drawn back until the spring plate or trigger 17 engages in the notch 13, and the marble is then inserted in the recess 7 between the strip 9 and the rubber band, and by slightly turning said marble the band will be disposed forwardly and its lower edge will lightly engage the marble so as not to retard its progress. The device is then placed upon the ground and pointed in the direction the marble is to take, and by depressing the spring plate or trigger 17 the rod or plunger is released and will shoot the marble with considerable force and accuracy. It will be noted that the marble is centered directly in front of the rod or plunger and that the latter acts on the marble in the same manner as a cue on a billiard ball to drive the marble in a straight line. As will be readily understood the device may be used in various games where it is desired to shoot a marble.

In some instances I may actuate the rod or plunger by means of a coil spring, but the rubber band is preferred inasmuch as it not only provides the means for actuating the rod or plunger but also serves to retain the marble in place. Furthermore, by providing an ordinary rubber band as the actuating means the same may be renewed at very small cost.

Having described my invention, I claim:

1. A marble-shooter, comprising a block having a recess in its forward end to receive the marble and a longitudinal bore communicating with said recess, a rod or plunger working in the bore and adapted to be projected through and beyond the recess, a rubber-band extending around the block, said rubber-band engaging the rod or plunger to actuate the same and extending across the front of the recess in the block to loosely engage the marble, and a trip device for holding the rod or plunger retracted, substantially as shown and described.

2. A marble-shooter, comprising a block having a vertical recess at its front end and an upwardly projecting portion at its rear end, a rod or plunger working longitudi-

nally through the block and center of the aforesaid recess, said rod or plunger having a notch at the underside of its forward end, 55 an L-shaped spring plate attached at one end to the upwardly projecting portion of the block and so that its other end will depend in the recess, said depending end of the plate having an opening through which the rod or 60 plunger projects, and a rubber band extending around the sides and ends of the block and around the rear end of the rod or plunger, substantially as shown and described.

3. A marble-shooter, comprising a block 65 having a vertical recess at its front end, and a longitudinal bore entering the center of said recess, a strip attached to the bottom of the block and forming a bottom for the aforesaid recess, a rod or plunger slidable 70 in the bore and having a notch at its forward end, a rubber band passed around the sides and ends of the block and across the rear end of the rod or plunger, said rubber band also extending across the front of the recess in 75 the block near the upper end thereof, and a bent spring plate attached to the top of the block and having an opening through which the rod or plunger projects, substantially as shown and described.

4. A marble-shooter, comprising a block 5 having a vertical recess at its front end with rearwardly converging side walls 8, said block also having a longitudinal bore entering the recess between the side walls thereof, 85 a rod or plunger slidable in the bore and having a notch at its forward end, a rubber band extending around the sides and ends of the block and across the rear end of the rod or plunger, said rubber band also extending 90 across the recess in the front of the block near the upper end thereof, and an L-shaped plate secured at one end to the top of the block and provided at its other end with an opening through which the rod or plunger 95 projects, substantially as herein shown and described.

In testimony whereof I have signed my name to this specification in the presence of two subscribing witnesses.

GEORGE S. RACKLYEFT.
